Primary Examiner — Lilyana Bekic*(74) Attorney, Agent, or Firm* — Johannes P. M. Kusters(57) **CLAIM**

The ornamental design for a respirator filter, as shown and described.

DESCRIPTION

FIG. 1 is a perspective view showing the new design for a respirator filter;

FIG. 2 is a top view thereof;

FIG. 3 is a right side view thereof, the left side view being a mirror image thereof;

FIG. 4 is a back view thereof; and,

FIG. 5 is a front view thereof.

The broken lines in the drawings depict portions of the respirator filter that form no part of the claimed design.
